CLAIM

The ornamental design for a smoke detector battery interface, as shown and described.

DESCRIPTION

FIG. 1 is a front perspective view of a smoke detector battery interface showing the new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a left side view showing the smoke detector battery interface in the context it is intended to be used.

The dashed lines form no part of the claimed design.
